[57] CLAIM

The ornamental design for a housing for a thermocouple connector head, as shown.

DESCRIPTION

FIG. 1 is an exploded perspective view of a housing for a thermocouple connector head showing my new design;

FIG. 2 is a front elevational view thereof;

FIG. 3 is a side elevational view thereof;

FIG. 4 is a left side elevational view thereof;

FIG. 5 is a bottom plan view thereof; and

FIG. 6 is a top plan view thereof.
